UNITED STATES PATENT OFFICE

RALPH D. NYE, OF WHEELING, WEST VIRGINIA, ASSIGNOR, BY MESNE ASSIGNMENTS,
TO SMITH ENGINEERING WORKS, OF MILWAUKEE, WISCONSIN, A CORPORATION
OF WISCONSIN

CRUSHER

Application filed August 21, 1929. Serial No. 387,478.

This invention relates to improvements in crushers, being more particularly directed to a double acting jaw crusher, in which the jaws are actuated by an eccentric shaft.

The primary object of the invention is the provision of a crusher having novel features of construction and which is of a simple and economical construction and highly efficient in operation.

A further object of the invention is the provision of a crusher of the double acting jaw type, in which the jaws are of a novel construction and supported upon the eccentric drive shaft in a novel and improved manner.

A still further object of the invention is the provision of a crusher in which the eccentric drive shaft is provided with tapered roller bearings for rotatably supporting the upper ends of the crusher jaws.

A still further object of the invention is the provision of a crusher in which novel means are employed to provide for the independent adjustment of the lower ends of the movable crusher jaws.

Other novel features of the invention and improved results of the crusher embodying the present invention will appear from the following description, taken in conjunction with the accompanying drawings.

In the drawings,

Figure 1 is a side elevation of a crusher constructed in accordance with the present invention, one-half of the figure being broken away and shown in vertical section.

Figure 2 is a view in side elevation, taken at right-angles to Fig. 1, a portion of the view being broken away and shown in vertical section.

By reference to the drawings, it will be seen that I have provided a crusher of the double-acting jaw type, which is of a construction to be used for the crushing of ores, stone or similar material.

Describing the invention in detail and re-

ferring to the drawings illustrating the invention in which I have designated similar parts by like reference numerals, 5 represents a suitable frame which is of a more or less rectangular shape and upon which are supported the working parts going into the make-up of the crusher. Although it is not essential the frame is preferable ribbed as illustrated at 6.

An eccentric shaft 7 is supported upon the frame by suitable outboard bearings 8, which are of the roller-bearing type and are supported upon the upper edges or ends of the end-walls of the frame. This shaft is provided with a belt wheel 9, for connection with a suitable source of power for the purpose of the rotation of the eccentric shaft to drive the movable crusher jaws A and B. At the opposite side of the crusher frame from the belt wheel, there is preferably provided a balance wheel 10 on the shaft 7.

The interior side-walls of the frame are provided with detachable and interchangeable crusher face plates 11, while the outer faces of the movable crusher jaws are provided with interchangeable and detachable crusher face-plates 12.

Referring now to the eccentric shaft, it will be seen that that portion 13 of the shaft which is supported in the outboard bearings 8 is tapered and carries a tapered bushing 14. That portion of the eccentric shaft which spans the open top of the crusher frame is enlarged centrally as appears at 15, and at either side of this enlargement and upon the shaft are roller bearings C and D, which are tapered bearings, as will appear from the following detailed description:

These roller bearings C and D are mounted in what I have termed cartridges, which comprise a circular housing 16 having at one end a depending end-wall 17, while their opposite ends are closed by an adjusting plate 18 fastened to the housing by a plurality of bolts 19. The rollers are indicated at 20 and

as clearly appears are set or carried in the races 21, at oblique angles and are held in the races by rings 22 and 23, which have tapered faces 24 bearing against the rollers.

- 5 The depending end-wall 17 of the housings or cartridges are provided with circumferential flanges 25 against which the rings 23 abut, while the rings 22 are in abutting engagement with the circumferential flanges 10 26 of the adjusting plate 18, the lower end of which plate is provided with a felt or other suitable backing 27, in engagement with the enlarged portion 15 of the eccentric shaft. The depending wall 17 of the housing 15 is also provided with a felt or other packing engagement with the eccentric shaft, thus making the cartridges grease-tight.

The two bearings C and D are identical in construction and the construction just described makes them independently and separately adjustable to take up and compensate for wear and they are provided with a connection 29, whereby grease or other lubricant can be delivered into the cartridges.

- 25 The outboard bearings are also identical in construction and are also provided with an adjusting means which is similar to that just described in respect to the inboard bearings C and D, so that a specific description 30 of them is not necessary.

Referring now to the movable crushing jaws A and B, it will be seen that they are identical in construction and that their upper ends 30 are rounded both internally and externally and that the internal rounded portions form half-bearings 31, which are in engagement with the external faces of the cartridges or housings 16, of the inboard bearings C and D, and resiliently held in supported 35 relation therewith, by reason of the arms or rods 32, the inner ends of which are in the form of eyes 33, having engagement with a common shaft 34, which shaft is in turn supported from the inboard bearing housing 16, by rods 35, while the outer ends of the arms or rods 32 pass through suitable housings 36, provided in the movable crusher jaws and have their outer ends terminating in a bolt-head 37 backed by a washer or plate 38, which 40 is adjustably positioned on the arm by a nut 39. A coiled spring 40, or its equivalent, is mounted in the housing 36 and has its one end in engagement with the housing bottom 41, while its upper end engages a floating plate 45 or washer 42, which is loosely mounted on the reduced portion 43 of the arm below or back of the adjusting nut 39.

By reason of the construction just described, the half-bearing portions at the upper ends of the movable crusher jaws are resiliently held in supported relation upon the inboard bearings C and D.

- 60 The spaces between the extreme upper ends of the movable carrier jaws are closed by a 65 detachable plate 44 and by reference to Fig.

2 of the drawings, it will be seen that by removing this plate access can be had to the upper ends of the lubricant delivering pipes 29 of the inboard bearings.

Attention is directed to the fact that the upper ends 30 of the pressure jaws A, B, have overlapping or interlocking connection upon the tops of the housings or cartridges so that these ends of the pressure jaws contact over a complete one-half surface of the circular 75 housings or cartridges 16.

Centrally disposed of the bottom of the frame, I have provided a channel iron 45 having channels in its opposite sides adjacent the lower ends 46 of the movable crusher jaws. Wedges or plates 47 are suitably mounted in the channels of the channel iron and are provided with a plurality of notches or grooves 48 for adjustably and rotatably receiving the inner rounded ends 49 of the toggles 50, the outer rounded ends 51 of which are in rotatable engagement with a suitable groove or depression 52 in the inner faces of the lower ends of the movable crusher jaws.

90 To hold the ends of the toggles in their respective seats, I have provided coiled springs 53, one end of which are connected as at 54 to the lower ends of the movable crusher jaws, while their opposite ends are connected to eye-bolts 55, or the like, which by 95 reason of nuts 56 are adjustably connected to the channel iron 45.

From the foregoing, it will be seen that I have provided a crusher having all the advantages previously enumerated. The movable 100 crusher jaws are mounted in a new and novel manner upon inboard bearings of a novel construction to permit their individual and separate adjustment, and I have further provided means for providing independent adjustment of the lower ends of the movable crusher jaws, and at the same time have kept the construction limited to one which is simple and permits of economical manufacture, yet at the same time produces a crusher which is strong and highly efficient in operation.

Having thus described my invention what I claim and desire to secure by Letters Patent is:

1. A crusher comprising a frame, a pair of stationary jaws and a pair of movable crusher jaws, a drive shaft transverse said frame and supported thereby, and the upper ends of said movable crusher jaws having resilient supporting connection with said shaft.

2. A crusher comprising a frame, a pair of stationary jaws and a pair of movable crusher jaws, an eccentric drive shaft transverse said frame and supported in bearings mounted thereupon, the upper ends of said movable crusher jaws shaped to form half bearings, and said bearing portions of said crusher jaws held in resilient supporting connection with said shaft.

3. A crusher comprising a frame, a pair

- of stationary jaws and a pair of movable crusher jaws, an eccentric drive shaft for said movable jaws, said movable jaws positioned back to back and having formed in 5 their upper ends half bearings, and said half bearings resiliently held in supporting connection with said shaft to be actuated thereby, for the purpose described.
4. A crusher comprising a frame, a pair 10 of stationary jaws and a pair of movable crusher jaws, an eccentric drive shaft transverse said frame and supported in out-board bearings mounted upon the sides of said frame, in-board bearings surrounding said 15 drive shaft, a housing mounted upon said in-board bearings and fixed as to rotation, said movable crusher jaws positioned back to back and having in their upper ends half bearings for engagement with said housing, 20 and resilient means for holding said movable crusher jaw ends in engagement with said housing for supporting the jaws upon the shaft and in operative connection therewith.
5. A crusher comprising a frame, a pair 25 of stationary jaws and a pair of movable crusher jaws positioned back to back for co-operation with said stationary jaws, an eccentric drive shaft for said movable jaws, the upper ends of said movable jaws formed 30 to provide half bearings formed with concaved faces for supporting connection with said drive shaft, and resilient means below said drive shaft interconnecting said movable crusher jaws for holding the upper ends 35 of said jaws in supporting position upon said shaft.
6. In a crusher, the combination with a 40 frame and a drive shaft, of a pair of stationary jaws and a pair of movable crusher jaws, an eccentric drive shaft supported upon out-board bearings mounted upon said crusher frame, said drive shaft intermediate its length provided with bearings supporting a housing fixed in respect to rotation, a stationary shaft below said drive shaft and supported by said housing, said movable crusher 45 jaws positioned back to back and having concaved inner faces at their upper ends for engagement with said housing, resilient connection between said movable crusher jaws and said stationary shaft for holding the upper ends of the movable crusher jaws in 50 supporting position upon said housing, and means intermediate the lower ends of said movable crusher jaws for independent adjustment of said jaws for varying the openings between the movable crusher jaws and the stationary jaws.
7. In a crusher, the combination with a 55 frame and a drive shaft, of a stationary jaw and a movable crusher jaw, said drive shaft supported upon out-board bearings mounted upon said crusher frame, an in-board bearing on said drive shaft and rotatable therewith comprising roller bearings 60
- mounted at an angle to said shaft and held in place by tapered rings, a housing supported upon said rings and fixed as to rotation, said housing provided with an adjusting plate engaging said tapered rings for 70 moving said rings to keep the housing in proper adjustment in respect to the roller bearings, and said movable crusher jaw resiliently held in supporting connection with said housing, for the purpose described. 75
8. A crusher comprising a frame, a pair of stationary jaws and a pair of movable crusher jaws, an eccentric drive shaft transverse said frame and supported thereby, 80 bearings carried by said drive shaft and rotatable therewith, housings supported upon said bearings and fixed as to rotation, means to adjust said housings in respect to said bearings, a stationary shaft positioned below said drive shaft and supported by said housings, 85 the upper ends of said movable crusher jaws formed with concaved faces for engagement with said housings, the said crusher jaws positioned back to back and provided with chambers, rods in said jaw chambers having 90 connection at their inner ends with said stationary shaft, and coil springs in said crusher jaw chambers resiliently connecting said jaws with said rods to resiliently hold the upper ends of said movable crusher jaws 95 in supported position upon said housings.
9. A crusher comprising a frame, a pair 100 of stationary jaws and a pair of movable crusher jaws, an eccentric drive shaft transverse said frame and supported thereby, bearings carried by said drive shaft and rotatable therewith, housings supported upon 105 said bearings and fixed as to rotation, means to adjust said housings in respect to said bearings, a stationary shaft positioned below said drive shaft and supported by said housings, the upper ends of said movable crusher jaws formed with concaved faces for 110 engagement with said housings, the said crusher jaws positioned back to back and provided with chambers, rods in said jaw chambers having connection at their inner ends with said stationary shaft, coil springs in 115 said crusher jaw chambers resiliently connecting said jaws with said rods to resiliently hold the upper ends of said movable crusher jaws in supported position upon said housings, and means intermediate the lower ends of said crusher jaws to provide independent adjustment of the jaws to vary the size of the openings between the movable 120 and stationary crusher jaws.
10. In a crusher, the combination with a frame and a drive shaft, of a pair of stationary jaws and a pair of movable crusher 125 jaws, the upper ends of said jaws provided with half bearings for engagement with said shaft to be supported and actuated thereby, a fixed member intermediate the lower ends of said movable crusher jaws, toggles loosely 130

- mounted between said stationary member and the lower ends of said movable crusher jaws to hold them in spaced relation in respect to said fixed member, resilient means
5 to hold the upper ends of the crusher jaws in engagement with the shaft, and resilient means at the lower ends of said crusher jaws to hold the loosely mounted toggles in operative position.
- 10 11. A crusher comprising a frame, a pair of stationary jaws and a pair of movable crusher jaws, an eccentric drive shaft transverse said frame and supported thereby, the upper ends of said movable crusher jaws having interlocking connection one with the other and having resilient supporting connection with the said shaft, for the purpose described.
- 15 12. In a crusher, the combination with a frame and a drive shaft, of a pair of stationary jaws and a pair of movable crusher jaws, said crusher jaws having their upper ends interlocked and supported upon a housing having therein a bearing through which
20 said drive shaft passes and the ends of said shaft beyond said housings being supported upon bearings mounted upon said crusher frame.
- 25 13. A crusher comprising a frame, a pair of stationary jaws and a pair of movable crusher jaws, and an eccentric drive shaft transverse said frame, the upper ends of said movable crusher jaws shaped to form half bearings in a series of finger extensions having interlocking overlapping connection with one another, and said finger half bearing portions of said crusher jaws engaging said drive shaft and supporting the jaws in operative positions.
- 30 14. A crusher comprising a frame, a pair of crusher jaws, one of said jaws being movable, a drive shaft, said movable crusher jaw having a portion shaped to form a half bearing, and said bearing portion of said crusher
35 jaw resiliently held in supporting connection with said shaft to be actuated thereby.
- 40 In testimony whereof I hereunto affix my signature.

RALPH D. NYE.
